United States Patent Office

Des. 207,925
Patented June 13, 1967

207,925

BOTTLE OR SIMILAR ARTICLE

Victor Koenigsberg, Franklin Square, N.Y., assignor to Colgate-Palmolive Company, New York, N.Y., a corporation of Delaware

Filed Oct. 1, 1964, Ser. No. 81,984

Term of patent 14 years

(Cl. D58—8)

Fig. 3

Fig. 1

Fig. 2

Fig. 4

Fig.5

Fig.6

Fig.7

Fig.8

FIG. 1 is a side elevational view of a bottle embodying my new design, the other side being substantially a mirror image thereof;

FIG. 2 is an end elevational view, the other end being substantially a mirror image thereof;

FIG. 3 is a top plan view; and

FIG. 4 is a bottom plan view thereof;

FIG. 5 is a side elevational view of another embodiment of my new design, the other side being substantially a mirror image thereof;

FIG. 6 is an end elevational view, the other end being substantially a mirror image thereof;

FIG. 7 is a top plan view; and

FIG. 8 is a bottom plan view thereof.

I claim:

The ornamental design for a bottle or similar article, as shown and described.
